UNITED STATES PATENT OFFICE.

OTTO LUHR, OF CHICAGO, ILLINOIS.

REFRIGERATOR CAR.

Application filed May 10, 1926. Serial No. 107,944.

REISSUED

The invention relates to rail road cars, and more especially to cars commonly known as refrigerator cars.

The object of the invention is to provide a car having a refrigerating mechanism attached thereto and adapted to keep the temperature in the car substantially at a predetermined degree of temperature whether the car be in transit or at stand still.

Another object of the invention is to provide a refrigerator car having a suitable compressor attached thereto on any suitable place on the car, for instance on the under side of the under-frame of the car.

A further object of the invention is to provide a refrigerator car the bulk heads whereof containing the refrigerating coils will occupy a relatively small space leaving ample room for the freight to be loaded in the car.

Another object of the invention is to provide a car having condenser coils or pipes arranged on the outside of the car, preferably on top of the car, whereby the heat absorbed by the refrigerating medium may be carried off by the draft produced by the movement of the car.

A still further object of the invention is to provide a refrigerator car the compressor whereof is driven directly by one of the car wheels or car axles.

Another object of the invention is to provide a refrigerator car, wherein the driving mechanism for the compressor is constantly in frictional contact with one of the wheels or axles of the car, regardless if the car travels on a straight track or on a curve.

Other objects of the invention not specifically mentioned will be evident from the following specification.

The accompanying drawings show an embodiment of the invention. It is however to be understood, that the invention is not to be limited to the exact construction shown in said drawings and described in said specification, but that changes may be made as long as said changes fall inside the scope of the claim appended hereto.

In the drawings:

Fig. 1 is a top view of the car, a part of the condenser coils and the roof of the car being broken away.

Fig. 2 is a partial vertical longitudinal section.

Fig. 3 is a partial top view of Fig. 2.

Fig. 4 is a vertical section showing the

brine tank containing the refrigerating coil and some pipe connections thereof.

Fig. 5 is a vertical cross section through a bulk head of the car, and

Fig. 6 is a vertical cross section through the top portion of the car.

A compressor 6 of suitable construction is fastened underneath the underframe 7 of the car. It is to be understood however, that the invention is not to be limited to this exact arrangement. The compressor 6 may be arranged on any suitable place on the car and such arrangement would still be within the spirit and the scope of the invention. The compressor is driven by means of a flexible shaft 8 journaled at one end in the casing of the compressor 6 and at its other end in a bearing 9 fastened to the bolster 10 of the truck of the car. A friction wheel 11 is fastened to the end of the flexible shaft adjacent the bearing and is in permanent frictional contact with a car wheel 12. This contact will not be interrupted, when the car travels around a curve, because the truck moves as an integral unit, and the bearing 9 supporting the flexible shaft 8 is an integral part of the truck.

From the compressor 6 a pipe 13 leads to the condenser coils 14. These condenser coils 14 are shown as arranged on the top of the car and this is the preferred arrangement. It is however to be understood, that the invention is not to be limited to this specific arrangement of the condenser coils,

but that the latter may be disposed at any suitable place on the car, as long as the draft produced by the travel of the car is enabled to come into contact with substantially the entire surface of the pipes forming the condenser. Preferably the pipe 13 leading from the compressor 6 to the condenser 14 is connected with the latter by means of connecting pipes 15. Said connecting pipes communicate with the pipe of the condenser located adjacent the peak of the roof of the car, so that the condensed refrigerating medium will flow downwardly through the condenser pipes. The lowest part of said condenser 14 communicates with a pipe 16,

105 which in turn is connected with a pipe 17 leading to a liquid receiver 18 located in one of the bulk heads of the car, as shown in Fig. 5.

A pipe 19 leads from the liquid receiver 110 18 to the lower end of the refrigerator coil 20, and from the upper or outlet end of this

coil a pipe 21 leads to a connecting pipe 22 communicating with the compressor.

The refrigerator coil 20 is disposed in a brine tank 23. The usual refrigerator cars are provided with two bulk heads, and it is preferred to arrange one brine tank with a refrigerator coil therein in each bulk head as shown in Fig. 1. The tank 23 is not fully as high as the refrigerating coil 20, so that the lower portion of the coil is surrounded by a weak brine solution, which will be frozen at times solidly under the influence of the refrigerating medium contained in the coil. The upper portion of the coil extends upwardly of the tank and will absorb heat directly from the air in the car. In order to provide the biggest possible cooling surface for cooling the air in the car the wall of the brine tank is made of corrugated sheet metal, and in addition to that, an air shaft 24 is provided centrally of the tank and extending throughout the entire height of said tank. The coil 20 surrounds the wall of the air shaft 24. The direct cooling of the air in the car is therefore effected by the exposed coil surface and the surfaces of the brine tank.

The refrigerating medium travels from the liquid receiver 18 in liquid state to the bottom of the refrigerating coil 20, where it will be gasified by the absorption of heat from the car, from the top of this coil to the compressor 6 and from there to the condenser coil 14, where it gives off all the heat absorbed from the air in the car and from the brine in the tanks 23 to the open atmosphere, whereupon it returns in liquid state to the liquid receiver.

As long as the car is in motion, the refrigerating medium will be kept in circulation, thereby cooling the car and causing the brine in the tanks to freeze solid.

Should the car for one reason or another be detached from the train and remain for a relative long period of time on a siding remote from a station and any icing or stationary refrigerating facilities, the solid ice blocks formed by the brine will keep the car at the desired temperature.

What I claim as new and desire to secure by Letters Patent is:

In a refrigerator car of the class described the combination of a bulk head forming a part of the car, a brine tank located in said bulk head, a central air shaft in said tank, a refrigerator coil arranged in the brine tank, surrounding the air shaft and partially extending outside of the tank, a compressor fastened on the outside of the car, a flexible shaft adapted to drive the compressor, a bracket fastened to one of the trucks of the car and supporting the free end of the flexible shaft, a friction wheel fastened to the end of the shaft adjacent the bracket and in permanent frictional contact with the running gear of the car, said compressor communicating with the outlet end of the refrigerating coil, a condenser located on top of the car and communicating with the compressor, and a liquid receiver arranged adjacent the brine tank and communicating with the intake end of the refrigerating coil and with the condenser.

In witness whereof I have affixed hereunto my signature.

OTTO LUHR.
